UNITED STATES PATENT OFFICE.

SOLOMON RICH, OF WEST ORANGE, NEW JERSEY.

DETACHABLE MATRIX-STORAGE MAGAZINE FOR TYPOGRAPHICAL MACHINES.

Application filed February 2, 1927. Serial No. 165,353.

This invention relates to improvements in detachable matrix storage magazines for typographical machines, and the same has reference, more particularly to a manipulatable means for releasing the magazine from locked relation to a typographical machine in combination with a rotary matrix locking bar so that said manipulatable means is itself locked against actuation when the matrix locking bar is turned to open or matrix releasing position, but released for actuation when said matrix locking bar is turned to closed or matrix locking position.

The present invention has for its principal object to provide in combination with a rotary matrix locking bar for typographical machine magazines, a manually operative releasing bolt slidably mounted at one side of the magazine to coact with the devices for locking the magazine in operative assembled relation to the machine, said rotary matrix locking bar having means movable by its rotation into and out of operative relation to said releasing bolt, whereby the latter is itself automatically locked against manipulation when the matrix locking bar is in matrix releasing position, and automatically released for manipulation when the matrix locking bar is in matrix locking or obstructing position.

Other objects of this invention, not at this time more particularly enumerated, will be clearly understood from the following detailed description of the same.

The invention is clearly illustrated in the accompanying drawings, in which:

Figure 1 is a plan view of the discharge end portion of a matrix storage magazine, having the novel interrelated manipulatable magazine locking latch actuating means and rotary matrix locking bar made according to and embodying the principles of the present invention;

Figure 2 is a longitudinal detail section of the magazine cover plate, taken on line 2-2 in Figure 1, showing the rotary matrix locking bar in magazine closing position and in released relation to the magazine locking-latch actuating means;

Figure 3 is a fragmentary plan view of a portion of said magazine cover plate, with the keeper plate for said magazine locking-latch actuating means removed;

Figure 4 is a fragmentary bottom plan view of said magazine cover plate with the rotary matrix locking bar and the magazine locking-latch actuating means;

Figure 5 is a detail cross-section, taken on line 5-5 in Figure 4;

Figure 6 is a detail longitudinal section on an enlarged scale, taken on line 6-6 in Figure 3;

Figure 7 is a detail transverse section on an enlarged scale, taken on line 7-7 in Figure 3, and showing the rotary matrix locking bar in magazine closing position;

Figure 8 is a view similar to that shown in Figure 7, but illustrating the rotary matrix locking bar in magazine opening position; and

Figure 9 is a detail perspective view showing the interrelation of the rotary matrix locking bar and the magazine locking-latch actuating means.

Similar characters of reference are employed in all of the above-described views to indicate corresponding parts.

Referring to said drawings, the reference character 10 indicates the matrix storage magazine, in the usual grooved ways of which are stored the matrices 11 subject to downward feeding movement through and discharge from the magazine under the control of the usual escapement devices (not shown), in the manner well known to those familiar with typographical machines.

The upper wall of the magazine terminates in a cover plate 12 which borders the discharge end thereof. Said cover plate possesses on its outer side a transverse boss or enlargement 13. The under side portion of said cover plate, in alignment with said boss or enlargement, is transversely bored to provide a bearing seat 14 for a rotary matrix locking bar 15. Said locking bar 15 is thus mounted for rotation on its longitudinal axis, so that proper turning movements thereof will selectively position the same in either matrix releasing or locking position.

That portion of the rotary locking bar 15 which extends across the continuation of the matrix guide grooves 16 formed in the under side of the cover plate 12, is cut away to provide a flat face forming a matrix engaging abutment 17, which is shiftable, by rotation of the locking bar, either into substantially horizontal or substantially vertical plane relative to the plane of the magazine; so that in the former position the flat face of the bar is flush with the bottoms of the grooves 16, thus permitting the matrices to pass; but in the latter position one marginal portion of the abutment 17 is pro-

jected across the grooves 16, thus obstructing outward movement of the matrices; all as shown and described in detail in the copending application for United States Letters Patent, Serial No. 118,182, filed on or about June 24, 1926, by Charles E. Ireland.

Means are provided in connection with one end of the rotary matrix locking bar 15 both to manipulate it for turning movement, and to retain the same in its respective active and inactive positions. In preferred form, this means comprises at one end, preferably the right hand end, of the locking bar 15, a square shank 18 having at its free end a screw-threaded portion 19. Slidably engaged on said square shank 18, so as to turn with the locking bar 15, is the hub 20 of a knob or finger-piece 21. Extending axially into the interior of said knob and its hub from the outer end thereof is a socket or bore 22. Screwed upon the threaded portion 19 is a nut 23, and disposed around the shank 18 intermediate the inner end of said socket or bore 22 and said nut 23 is a compression spring 24. Secured to the adjacent end of said cover plate 12 to project toward the annular peripheral portion of the knob or finger-piece 21 is a stop-pin 25. Provided in the inner face of said annular peripheral portion of said knob or finger-piece 21 are a pair of stop sockets 26 and 27, in which the free end of said stop-pin 25 may be selectively engaged to retain the locking bar 15 in either its active matrix locking position or its inactive matrix releasing position, all in the manner also set forth in the aforesaid pending application of Ireland.

In typographical machines, and especially in so-called linotype machines, locking devices for locking the matrix storage magazines into the machine are provided. It is desirable that such locking devices be not released until the matrix locking bar has been turned to active position to hold the matrices against escape from the magazine when the latter is removed from the machine. In order, therefore, to guard against the removal of the magazine by an operator before the matrices are locked against escape, the instant invention provides in connection with the magazine itself a manipulatable means for releasing the magazine locking devices, said manipulatable means being so interrelated with the rotary matrix locking bar that it cannot be actuated until said locking bar is turned to matrix locking position. A common form of magazine locking mechanism, which may be taken as illustrative of one type subject to operation by the novel manipulatable releasing means with which the magazine is provided in accordance with the principles of the instant invention, serves also to hold the escapement carrying frame 28 in upwardly lifted opera-

tive relation to the magazine. This form of locking mechanism comprises a pair of laterally swinging arms 29 pivotally connected respectively with the sides of the escapement carrying frame 28. Each arm 29 carries a pivotally mounted spring pressed latch 30, which are respectively engageable in locking relation to the respective sides of the magazine 10. Arranged to cooperate with one of said swinging arms 29 is a suitably supported slidable bolt 31, having a nosing 32 operatively engageable with a recess 33 in the side of said swinging arm, so that, when thus engaged, the latter is retained against outward movement permitting the disengagement of the latch 30 from locked relation to the magazine. Operatively related to the bolt 31 is a transversely slidable plate 34 having an oblique cam portion 35 which coacts with a corresponding oblique slot in the body of said bolt 31, whereby transverse movements of said plate 34 will produce movements of said bolt 31 toward or away from the swinging arm 29 to engage or disengage the nosing of the former from the recess of the latter, as the case may be. Said slidable plate 34 is provided at its inner side with a raised nose 36 against the rearward side of which bears a thrust spring 37, to thereby normally but yieldably hold said slidable plate 34 moved toward the side of the magazine 10, and operative to hold the bolt 31 projected to engage its nosing 32 in the recess 33 of the arm 29.

Formed in the left hand side or end of the cover plate 12 of the magazine 10, and in the boss or enlargement 13 thereof, is a slideway 38, in a plane above the plane of said rotary matrix locking bar 15, and in opposed alignment with the nose 36 of the slidable cam plate 34 of the above described magazine locking mechanism. Slidably engaged in said slideway 38 is a manipulatable actuator member 39, having at its outer end a downwardly extending projection 40, which by engagement in a recessed portion at the side of said cover plate 12, limits the normal retractive movement of said actuator member. Interconnected between the inner end of said slideway 38 and the inner end of said actuator member 39 is a pull spring 41, for retracting the latter to normal inactive position. The boss 13 of said cover plate 12 is provided on its forward side with an opening 42 leading outwardly from the slideway 38 through which may exteriorly project a finger-piece 43 connected with and by means of which the actuator member 39 may be manipulated at proper times. A keeper plate 44 secured to the boss 13 by screws 45, or other suitable fastening means, overlies the slideway 38 and retains the actuator member and its spring against displacement therefrom. Extending between the bearing seat 14 of the rotary matrix

locking bar and the bottom of the slideway 38 is a communicating opening or passage 46. Secured to said rotary matrix locking bar 15, to project laterally therefrom, is a 5 detent stud 47, which, upon rotation of said locking bar 15 to matrix releasing position is caused to swing upwardly through said opening or passage 46 into engagement with a detent-notch 48 provided in the under side 10 of the actuator member 39 to thereby lock the latter against outward movement or operative manipulation so long as the locking bar 15 remains in matrix releasing position (as shown in Figure 6); but, when said 15 locking bar 15 is rotated to matrix locking position, said detent stud 47 is swung, by such movement, out of the detent notch 48, thus freeing said actuator member 39 for manipulation (as shown in Figure 2).

20 It will be clearly evident from the above description, that, by the novel interrelation of the rotary matrix locking bar 15 and the actuator member 39, the latter cannot be manipulated to release the magazine locking 25 mechanism until the operator has turned the matrix locking bar 15 to matrix engaging position, and consequently risk of inadvertent removal of the magazine from the machine before the matrices are locked 30 against escape is eliminated. When, however, the operator has once turned the locking bar 15 to matrix engaging and retaining position, whereby at the same time the detent stud 47 is removed from the detent 35 notch 48 of the actuator member 39, then the operator may manipulate the latter to release the magazine locking mechanism so as to permit of the removal of the magazine from the machine. To operatively manipulate the actuator member 39, the operator 40 presses outwardly on the finger-piece 43 thereby causing an outwardly projecting movement of the actuator member against the tension of the spring 41. The outward 45 projection of the actuator member, thus produced, thrusts its exterior end against the nose 36 to thereby press outwardly the slideable plate 34, and through the action of the cam portion 35 of the latter relative to the bolt 31 causing a retraction of the latter, thus freeing the arm 29 and its latch 30 for 50 removal from locked relation to the magazine 10, all of which will not only be well understood by those skilled in the art, but 55 the attendant advantages in compelling the operator to first lock in the matrices before removing the magazine from the machine will be fully appreciated.

60 It will be understood that I do not limit the instant invention for use only with the specific type of magazine locking mechanism above described, since there are other forms and styles of locking mechanism with which the instant invention may be associated.

65 It will also be obvious that various

changes may be made in the general arrangements and combinations of parts making up the instant invention within the scope of the appended claims. Hence, I do not limit myself to the exact arrangements and combinations of the various devices and parts as above described in the foregoing specification, nor to the exact details thereof as illustrated in the accompanying drawings, except as may be required by the limitations 70 specified in the appended claims. 75

I claim:

1. In a typographical machine, a removable matrix storage magazine having adjacent to its discharge end a rotatable 80 matrix locking bar provided with a portion movable by rotation of said bar into or out of the path of movement of the matrices stored therein, means to hold said magazine against removal from said machine, releasable means to lock said holding means in operative position, an actuator member slidably mounted at one side of said magazine, said actuator member being manually movable to release said lock means, and means 85 on said matrix locking bar to engage and restrain said actuator member against manipulation when said bar is turned to matrix releasing position.

2. In a typographical machine, a removable matrix storage magazine having a rotatable matrix locking bar, holding means to retain said magazine in assembled relation to the machine, releasable means to lock said holding means in operative position, a 100 manipulatable member on said magazine to release said lock means, and interengageable means connected with said member and matrix locking bar cooperative to prevent manipulation of the former when the latter 105 occupies open position but disengaged to release the former for manipulation when the latter occupies closed position.

3. In a typographical machine, a removable matrix storage magazine having adjacent to its discharge end a rotatable matrix locking bar provided with a portion movable by rotation of said bar into or out of the path of movement of the matrices stored therein, means to hold said magazine against removal from said machine, releasable means to lock said holding means in operative position, a spring-retracted actuator member slidably mounted on said magazine adjacent to one end of said rotatable matrix locking 110 bar, said actuator member having an exteriorly projecting finger piece for manipulating the same to release said lock means, and means on said matrix locking bar to engage and restrain said actuator member 115 against manipulation when said bar is turned to matrix releasing position.

4. In a typographical machine, a removable matrix storage magazine having adjacent to its discharge end a rotatable matrix 120

locking bar provided with a portion movable by rotation of said bar into or out of the path of movement of the matrices stored therein, means to hold said magazine against removal from said machine, releasable means to lock said holding means in operative position, a spring-retracted actuator member slidably mounted on said magazine adjacent to one end of said rotatable matrix locking bar, said actuator member having an exteriorly projecting finger piece for manipulating the same to release said lock means, and means on said matrix locking bar to engage and restrain said actuator member against manipulation when said bar is turned to matrix releasing position, said latter means comprising a laterally extending detent stud fixed on the adjacent end portion of said matrix locking bar, said actuator member having a detent notch to receive said detent stud, and said detent stud being caused to enter said detent notch when said matrix locking bar is turned to matrix releasing position.

5. In a typographical machine as defined in claim 1, in which the matrix locking bar is provided at its opposite end with exteriorly disposed means for rotating the same, and means cooperative with said bar rotating means for selectively retaining said bar in

10 15 20 25 30

either matrix locking or matrix releasing position.

6. In a typographical machine as defined in claim 2, in which the matrix locking bar is provided at its opposite end with exteriorly disposed means for rotating the same, and means cooperative with said bar rotating means for selectively retaining said bar in either matrix locking or matrix releasing position.

7. In a typographical machine as defined in claim 3, in which the matrix locking bar is provided at its opposite end with exteriorly disposed means for rotating the same, and means cooperative with said bar rotating means for selectively retaining said bar in either matrix locking or matrix releasing position.

8. In a typographical machine as defined in claim 4, in which the matrix locking bar is provided at its opposite end with exteriorly disposed means for rotating the same, and means cooperative with said bar rotating means for selectively retaining said bar in either matrix locking or matrix releasing position.

In testimony that I claim the invention set forth above I have hereunto set my hand this 31st day of December, 1927.

SOLOMON RICH.
